ATTACHMENT FOR SPINNING MACHINES

William H. Porter, Moylan, and Norman Redman,
Philadelphia, Pa.

Application July 14, 1937, Serial No. 153,526

5 Claims. (Cl. 117—22)

This invention has to do with those machines that are employed for the purpose of twisting or spinning various types of fibres in the preparation of yarn.

At the present time in the preparation of yarn from the various types of fibres, such as animal, vegetable or artificial, machines known in the art as spinning machines, roving frames and twisting frames are employed, depending upon the particular nature of the work to be done and the yarn product desired. All of these machines have a feature in common, which is the inclusion of a feed roll over which the yarn that is being treated passes. This feed roll determines the speed at which the yarn is fed to the other instrumentalities of the particular machine.

There is to-day in the textile and related trades a very noticeable demand for a so-called irregular yarn; that is a yarn in which the diametrical dimension varies at different points along the yarn.

In order to satisfy this demand various attachments for spinning machines have been proposed, and which are effective to vary the speed at which the feed roll is driven; this variation being evidenced in the finished yarn in the irregular structure of the latter. However, the known attachments for this purpose have not proven to be entirely satisfactory, and this condition is attributed mainly to two features. The first is the complex nature of the now known attachments, and the second is the lack of sureness in their operation.

Another highly undesirable feature that is common to many of the known attachments is that they cause the feed roll of the spinning machine to be driven at a rate of speed lower than the normal minimum rate of speed of the machine.

With these conditions in mind this invention has in view as its foremost objective the provision of an attachment for spinning and similar machines of the character above noted. Which is designed to be operatively associated with the feed roll of the machine to effect the variation in speed of the latter, and in accordance with this invention this attachment is of a highly simplified nature, and operates with a degree of sureness heretofore unattained in this art.

The invention has in view as a further objective the provision of an attachment of the type set forth above, and which attachment is effective to increase the speed of the feed roller as occasion demands, but which attachment is never effective to reduce the normal operating speed of the feed roller.

In attaining these objectives in a practical embodiment the invention includes as an essential element the provision of a free wheeling mechanism that is mounted on the drive shaft for the feed rollers. As this drive shaft is driven the free

wheeling mechanism at no time is effective to reduce or interfere with the speed of the drive shaft to cause the latter to operate at a speed lower than the normal operating speed. However, certain other mechanisms are associated with the free wheeling device to cause the latter to increase the speed of the drive shaft at periodic or irregular intervals, as the case may be.

The invention has in view as a further somewhat more detailed objective the provision of an attachment for spinning machines of the character above noted, which is readily and easily adjustable to afford variations in the irregular thickness of the yarn which is produced. In order for an attachment of this type to be properly operable under practical commercial conditions it is necessary that the spinning machine to which it is attached be operable to produce an irregular yarn of any desired structure. Accordingly the invention includes as an important phase thereof this ease of adjustability.

Various other more detailed objects and advantages such as arise in connection with attaining the above objectives will in part become apparent, and in part be hereinafter stated, as the description of the invention proceeds.

The invention, therefore, comprises an attachment for spinning and similar machines which is designed to be operatively associated with the drive shaft for the feed roll of the machine, to provide increase in the speed of the drive shaft at periodic or irregular intervals, and which attachment is readily adjustable to afford variations in the periods at which the speed of the drive shaft is increased.

For a full and more complete understanding of the invention reference may be had to the following description and accompanying drawings, wherein—

Figure 1 is a side view showing certain parts in section, and other parts in elevation, of an attachment which is applied to a spinning machine in accordance with the precepts of this invention.

Figure 2 is a view taken at right angles to the showing of Figure 1. In this view only those parts of the spinning machine are illustrated which are necessary to bring out the mode of operation of the attachment of this invention.

Figure 3 is a view of an irregular piece of yarn which is spun on a spinning frame when the attachment of this invention is applied thereto.

Figure 4 is a detailed view in perspective of one part of the attachment.

Figure 5 is a showing partly in section and partly in elevation of the drive shaft for the feed rollers. The sectional part of this view is taken about on the plane represented by the line 5—5 of Figure 6.

Figure 6 is a section through the drive shaft of

Figure 5, and is taken about on the plane represented by the line 6—6 of Figure 5, and

Figure 7 is an enlarged detailed showing of the ratchet mechanism of the attachment.

- 5 Referring now to the drawings, wherein like reference characters denote corresponding parts, it is first important to note that while the attachment of the present invention is illustrated and described in conjunction with a spinning machine 10 such as is employed in the preparation of woolen yarns, it is to be clearly understood that the invention is not to be limited to this particular type of machine. The invention is adaptable for use on any machine employed for spinning, twisting or roving purposes on yarns of any fibrous makeup, such as animal, vegetable or synthetic, and in which machine there is a feed roll which controls the speed at which the yarn is fed to the machine.
- 20 Referring more particularly to Figure 2, certain parts of a spinning machine with which this invention is particularly concerned are there illustrated. A shaft designated 10 is driven from a suitable source (not illustrated) and a plurality 25 of rollers 11 are carried by the shaft 10. The cylindrical surfaces of these rollers 11 may be roughened or corrugated, as occasion demands, to afford a proper gripping engagement with the yarn that passes thereover, and which yarn 30 is designated 12.

At the extremity of the machine on which the attachment of this invention is to be applied the shaft 10 drivably carries a pinion 13, and this pinion 13 is in mesh with a gear 14 that is non-35 rotatably mounted on a stub shaft 15. At this point it is well to note that the mountings in the framework for the various shafts herein illustrated and described are not shown in the drawings; this arrangement making for a better 40 and clearer illustration of the various operating parts. Thus the mountings for the shafts 10 and 15 are not illustrated.

The shaft 15 at its outer extremity carries another gear 16 that meshes with a gear 17 45 that is drivably connected with a feed roll drive shaft designated 18 by a free wheeling mechanism that is referred to in its entirety by the reference character 19. It is notable that free wheeling mechanisms such as that represented at 19 are well-known to those skilled in the 50 mechanical arts. However, the detailed construction of this free wheeling mechanism will be described hereinafter with reference to Figures 5 and 6.

55 The drive shaft 18 also carries, in a non-rotative relationship with respect thereto, a ratchet wheel designated 20, and which ratchet wheel is affected by certain mechanisms to be later described, to increase the speed at which 60 the shaft 18 is driven at periodic or irregular intervals. The shaft 18 extends back into the spinning machine, and carries feed rollers 21 over which the yarns 12 pass. Certain other rollers cooperate with the rollers 21 to maintain the 65 yarns in effective engagement therewith, and a comparable arrangement is employed in conjunction with the rollers 11.

With the shaft 10 driven at a constant speed the rollers 11 rotate at a constant speed. Due 70 to the gear reductions provided by gears 13, 14, 16 and 17 there is a speed differential between the speed rotation of the shaft 10 and the normal operating speed of the shaft 18, and this speed differential causes a drafting on the yarn in a 75 manner well-known to those skilled in the

spinning art. It is evident that the speed of rotation of the shaft 18 never falls below the normal operating speed. However, due to the free wheeling mechanism at 19 the ratchet wheel 20 is at times effective to increase the speed of rotation in a manner that will now be described.

Referring more particularly to Figures 1 and 7, the ratchet wheel 20 is shown as provided with ratchet teeth 22. Engaging with the ratchet teeth 22 are a pair of pawls designated 23 and 24. These pawls 23 and 24 are pivotally mounted, as shown at 25 and 26 respectively, on an arm 27 that is freely carried by the shaft 18. As shown at 28 and 29 the pawls 23 and 24 are spring pressed, and thus maintained in engagement with the teeth 22 of the ratchet wheel 20.

It is evident that when the arm 27 is stationary the ratchet wheel 20 may rotate in a counter-clockwise direction (speaking with reference to the showing of Figures 1 and 7) and the pawls 20 will merely ride over the ratchet teeth 22. Likewise, during any movement of the arm 27 in a clockwise direction the pawls 23 and 24 will ride over the ratchet teeth 22. However, if the arm 27 is urged in a counter-clockwise direction, the 25 pawls 23 and 24 engage the ratchet teeth 22 to cause a corresponding movement on the part of the ratchet wheel 20.

Pivotally connected to the arm 27 adjacent its free extremity, as represented at 30, is a link 31, 30 and this link 31 is connected at its other extremity, as shown at 32, to a triangularly shaped cam member 33. An arm 34 is pivotally mounted, as shown at 35, on the framework of the machine (not shown) and the cam member 33 is pivotally 35 mounted, as shown at 36, on the arm 34.

The cam plate 33 is provided with an arcuate slot 37 with which cooperates a threaded pin and nut assembly 38 that is carried by the arm 34. It is evident that the nut and pin assembly 40 38, together with the arcuate slot 37, provide means for adjusting the position of the cam plate 33 with respect to the arm 34.

An arcuate supporting arm 39 is formed with a correspondingly shaped slot 40 through which 45 passes a threaded bolt 41 (Figure 4) that extends into an appropriate socket in the framework of the machine, to securely hold the supporting arm 39 in position. Pivotally carried at the free end of the supporting arm 39 is a pivot pin 42, and carried by this pivot pin 42 is a cam carrier 43 which carries a plurality of cam rollers 44 that are mounted on bearing pins 45.

As clearly brought out in Figure 4, the cam carrier 43 is provided with a plurality of openings 46 which are threaded to receive the bearing pins 45. By threading these pins into appropriate openings 46 variations in the relative positions of the cam rollers 44 are afforded.

It is also notable that the cam carrier 43, illustrated in the drawings, may be replaced by a cam carrier of a larger or smaller size, as occasion demands, and provision is made for locating the pivotal center of the cam carrier at the proper point by the adjustability in the mounting of the 50 arm 39.

The peripheral edge of the cam carrier 43 is provided with gear teeth 47 that mesh with a pinion 48 that is carried by a gear 49. Meshing with the gear 49 is a driving pinion 50 that may 70 be driven from any suitable source, such as by the endless belt represented at 51 in Figure 1.

With the driving pinion 50 driven by the belt 51 in an appropriate constant rate of speed, the gear 49 is turned, and moving therewith is the 75

pinion 48. As the latter is in mesh with the gear teeth 48 on the cam carrier 43 the latter is moved to cause movement of the cam rollers 44 in a clockwise direction speaking with reference to the 5 showing of Figure 1. As each of the rollers 34 engages the cam 33 the latter is urged upwardly, and due to the fixed pivotal mounting 35 of the arm 34, the arm 27 is moved in a counter-clockwise direction to add an increment of speed to the 10 ratchet wheel 20 that is drivably mounted on the shaft 18.

This increase of speed on the part of the shaft 18 is permitted by the free wheeling assembly 19 that is clearly shown in Figures 5 and 6.

15 The gear 17 is shown as formed with an extension 52 having a socket 53 which receives the extremity of the shaft 18. On the side opposite the extension 52 the gear 17 carries a housing 54 which surrounds the shaft 18. When the shaft 20 20 18 is received in the housing 54 the shape of the latter, together with the cylindrical shape of the shaft 18 defines the somewhat crescent-like recesses shown in Figure 5 and designated 55.

Disposed in each of these recesses 55 is a roller 25 56, and a retaining plate 57 retains these rollers 56 in position. It is evident that with no power applied to the ratchet wheel 20 the shaft 18 will be driven by the gear 17 as the free wheeling mechanism 19 establishes the driving connection 30 between the gear 17 and the shaft 18. However, when the ratchet wheel 20 is actuated at a speed in excess of the normal operating speed of the shaft 18, the free wheeling mechanism permits the shaft 18 to freely rotate in the housing 54 and socket 52 at a higher rate of speed than that at which the gear 17 is driven.

It is now a known practice in the spinning art 40 to employ a spinning machine including two feed rolls, and pass yarn of one color over one feed roll and yarn of another color over the other feed roll, with the resulting yarn product comprising a blend of the two colors.

This invention contemplates the use of the attachment aforescribed with machines of this 45 type, as the attachment is readily applicable to each of the feed rolls.

While a preferred specific embodiment of the invention is hereinbefore set forth it is to be clearly understood that we are not to be limited to 50 the exact construction illustrated and described, because various modifications of these details may be provided in putting the invention into practice within the purview of the appended claims.

55 We claim:

1. In combination with a drive shaft of a spinning machine, a means for rotating the drive shaft at a regular operating speed, an attachment for increasing the speed of rotation of the 60 drive shaft over the regular operating speed at periodic or irregular intervals comprising a ratchet wheel nonrotatably mounted on the drive shaft, an arm freely mounted on the drive shaft adjacent to the ratchet wheel, a pawl carried by said 65 arm and engaging said ratchet wheel, and means for oscillating the said arm with a positive action, said means consisting of cam mechanism, and rigid and non-yielding mechanical linkage between the said arm and the said cam mechanism.

70 2. In combination with a drive shaft of a spinning machine, a means for rotating the drive shaft at a regular operating speed, an attachment

for increasing the speed of rotation of the drive shaft over the regular operating speed at periodic or irregular intervals comprising a ratchet wheel 5 drivably mounted on the drive shaft, an arm rotatably mounted on the drive shaft, a pawl carried by said arm and engaging the ratchet wheel whereby said arm is effective to drive the ratchet wheel in one direction of its movement, a link connected to said arm, a second arm having one end pivotally mounted in the framework of the 10 machine and the other end connected to said link, and cam means associated with said last mentioned arm causing oscillation of the same whereby the first mentioned arm is oscillated.

3. In combination with a drive shaft of a spinning machine, a means for rotating the drive shaft at a regular operating speed, an attachment for increasing the speed of rotation of the drive shaft over the regular operating speed at periodic or irregular intervals comprising a ratchet wheel 20 drivably mounted on the drive shaft, an arm rotatably mounted on the drive shaft, a pawl carried by said arm and engaging the ratchet wheel whereby said arm is effective to drive the ratchet wheel in one direction of its movement, a link 25 connected to said arm, a second arm having one end pivotally mounted in the framework of the machine and the other end connected to said link, a cam plate connected to said second arm and link respectively, said cam plate being adjustable with respect to said arm, a cam carrier pivotally mounted on the framework of the machine, cam rollers carried by the carrier and adapted to engage the cam plate to cause oscillation of said second mentioned arm, and which oscillation 30 through the said link causes oscillation of the first mentioned arm, and means for rotating said cam carrier.

4. In combination with a spinning machine including a feed roll, a drive shaft for the feed roll, 40 free wheeling mechanism on the drive shaft, and means for driving the drive shaft at a regular speed through the free wheeling mechanism, means for increasing the speed of rotation of the drive shaft over the regular operating speed at 45 periodic or irregular intervals comprising a ratchet drivably mounted on the drive shaft, pawl mechanism associated with the ratchet wheel for rotating said ratchet wheel in one direction, cam means for causing positive actuation of said pawl 50 mechanism, non-yielding mechanical linkage between the pawl mechanism and the cam means; and means for operating said cam means at periodic or irregular intervals.

5. An attachment of the character described 55 comprising a ratchet wheel adapted to be drivably mounted on the drive shaft of a spinning machine, an arm adapted to be rotatably mounted on the drive shaft of a spinning machine, a pawl carried by said arm and engaging said ratchet 60 wheel, a cam plate, operative connections between said cam plate and said arm whereby oscillation of the cam plate causes oscillation of the arm, a cam carrier adapted to be pivotally mounted on the framework of a spinning machine, means for 65 rotating the cam carrier, and a plurality of cam rollers carried by the cam carrier and adapted to engage the cam plate to cause oscillation thereof, said rollers being adjustable on the cam carrier.
